UNITED STATES PATENT OFFICE.

RUTHERFORD H. MARSH, OF IRWIN, PENNSYLVANIA.

RAIL-JOINT.

No. 927,987.

Specification of Letters Patent.

Patented July 13, 1909.

Application filed April 30, 1908. Serial No. 430,134.

To all whom it may concern:

Be it known that I, RUTHERFORD H. MARSH, a citizen of the United States of America, residing at Irwin, in the county 5 of Westmoreland and State of Pennsylvania, have invented certain new and useful Improvements in Rail-Joints, of which the following is a specification, reference being had therein to the accompanying drawing.

10 This invention relates to a rail joint, and the invention aims to obviate the necessity of using nuts and bolts as a fastening medium for the confronting ends of two rails. To this end, I have devised a novel rail chair 15 for supporting and embracing rails upon ties or sleepers, said chair being firmly spiked to the ties, to prevent lateral and vertical displacement of said rails.

The detailed construction entering into 20 my invention will be presently described, and reference will now be had to the drawings forming a part of this specification, wherein—

Figure 1 is a perspective view of my rail 25 joint. Fig. 2 is an end view of the same and Fig. 3 is a plan of a rail chair.

To put my invention into practice I construct a rail chair of a base plate 1, the inner edge of which is provided with an integral 30 splice bar 2, and with a plurality of spike notches 3. Contiguous to the outer edge of the base plate 1 is another splice bar 4, and between said splice bar and the outer edge of the base plate 1 is formed a plurality of 35 spike openings 5.

The rail chair as above described is counter-sunk or seated in recesses 6 provided therefor in ties 7, these ties being located close together and lower than the remainder 40 of the ties supporting the rails 8, in order that an even foundation will be provided for said rails. After the chair containing the confronting ends of the rails is correctly positioned, spikes 9 are employed for securing 45 the chair to the ties 7.

My improvement allows for the expansion and contraction of rails 8, and prevents lateral and vertical displacement to such an extent as would cause derailment of the rolling stock adapted to pass over the same. 50

It will be observed that the base plate 1 provides practically a continuous tread for the rails 8, consequently, I eliminate the jarring and bumping heretofore experienced when riding over a rail joint. 55

It is obvious that my invention is susceptible to such structural changes as are permissible by the appended claim.

Having now described my invention what I now claim as new, is:—

The combination with a plurality of ties each having a rectangular seat below the plane of its upper face, said seats being arranged in parallelism with respect to each other and each extending in the same plane 65 throughout and below the plane of the upper face of the tie whereby a pair of shoulders in each tie is provided, of a rail chair extending transversely with respect to the ties and mounted upon said seats, said rail chair 70 prevented from lateral displacement by said shoulders, said rail chair comprising a base plate for supporting the confronting ends of a pair of rails, a splice bar formed integral with the inner edge of said base plate, engaging the upper face of the base of said 75 rails and further engaging the lower face of the head of the rails, an outer splice bar formed integral with said base plate at a point removed from the outer edge of said 80 plate whereby a longitudinally extending flange is provided, said outer splice bar engaging the upper face of the base of the rails and further engaging the lower face of the 85 head of the rails, said flange formed with a plurality of openings, spikes extending through said openings and engaging in the ties, the marginal portion of the base of the inner edge of said base plate provided with 90 notches, spikes extending through said notches for connecting said inner splice bar to the ties.

In testimony whereof I affix my signature in the presence of two witnesses.

RUTHERFORD H. MARSH.
